NATHAN M. LOWER AND EDWIN ARCHER TURNER, OF PITTSBURGH, PENNSYLVANIA,
ASSIGNORS, BY MESNE ASSIGNMENTS, TO THE STANDARD STOKER COMPANY INC.,
OF NEW YORK, N. Y., A CORPORATION OF DELAWARE

LOCOMOTIVE STOKER

Application filed July 18, 1927. Serial No. 206,702.

The invention has special reference to the improvement in means for stoking locomotives, its object being to simplify and increase the durability and efficiency of the stoker and of a locomotive boiler.

A preferred embodiment of the invention is hereinafter described and is illustrated in the accompanying drawings, in which:

Fig. 1 is a detail central, vertical, longitudinal section of a locomotive and its tender and of the stoking mechanism;

Fig. 2 is a detail elevation of the inner face of the back head of the locomotive fire-box and of the stoking mechanism associated therewith; and,

Fig. 3 is a detail plan view of the stoking mechanism and of the locomotive and tender, some parts being shown in section.

In locomotives in which the fuel is introduced through an elevator located within the fire-box there has been a loss of efficiency because the stoking mechanism very materially reduced the grate area, and consequently the amount of fuel that could be burned, and because a substantial area of the backhead was cut off from the heat, thereby reducing the steaming capacity of the boiler, it has been impracticable to protect the elevator from the intense heat, and it would not only be quickly burned out, but was liable to be distorted by warping and rendered inoperative.

These and other serious objections to this type of stoking device are substantially overcome in the present invention.

The fire-box of the locomotive is indicated at 10, the backhead, which, as usual, is hollow, is shown at 11; the usual hand-firing opening is marked 12, and a portion of the grate is shown at 13. The cab deck or floor is indicated at 14; the floor of the tender at 15; the fuel bin at 16, and the usual coal gate at 17. The locomotive and tender are coupled together as usual, as shown at 18.

An aperture is formed in the backhead 11

near its lower margin but slightly above the mud ring 19. Within this aperture there is fitted a sleeve 20, making water-tight joints with the inner and outer walls of the backhead. Through this sleeve fuel is admitted 50 into the fire-box, being delivered thereto by conveying mechanism of any desired form, here shown as the jointed screw conveyor 21 housed within a jointed conduit 22 extending forwardly from below the floor 15 of the tender and receiving fuel through suitable openings in the floor 15, as is usual.

A tubular ball and socket unit comprising the elements 23, 24, is rigidly attached to the backhead in registry with the sleeve 20, the element 23 being laterally flanged to fit against the backhead, and being secured thereto by any suitable means. The element 24 of this unit takes the form of a sleeve 25 within which the forward end of the conduit 22 slidably fits. This sliding engagement permits relative movement of the conduit and joint due to the relative movement of the locomotive and tender, and also to the expansion and contraction of the fire-box. 70

Within the fire-box there is located an elevator conduit 26, closed at its bottom, and having a lateral aperture in register with the sleeve 20. The conduit 26 is firmly secured to the backhead by means of attaching lugs, such as 27, 28, shown in Figs. 1 and 2, and which may be as numerous and may be disposed as may be found advantageous. The elevator conduit may, therefore, be placed close to the backhead and parallel, or approximately so, with the inner face thereof. The length of this conduit may be varied. Usually, as shown, its upper end is approximately in line with the bottom of the hand-firing opening 12, thus bringing the fuel to a point of elevation substantially above the grate surface, while no interference with hand-firing occurs. Preferably the upper end of the conduit is surrounded by a collar 29 in the form of a plate, which 90

may be fitted upon or formed integral with the conduit 26 and forms a table giving direction to the fuel as it is projected into the fire-box by steam jets discharged from nozzle 30, located at the rearward side of the conduit. Suitable steam pipes leading to the nozzle 30 may be arranged in any preferred manner.

An elevating screw 31 is mounted within the conduit 26, its shaft having a bearing upon the bottom wall thereof. This shaft, or an attachable extension thereof, projects through the bottom wall of the conduit, as shown at 32, and carries a bevel gear 33, which meshes with a bevel gear 34 carried by a shaft 35 journaled in a gear casing 36 secured to the bottom end of the conduit 26. The shaft 35 is connected, by means of a universal joint 37, with a telescopically extensible drive shaft 38.

The fuel moving screws are driven by means of any suitable motor, such as the one conventionally shown at 39, and which actuates a worm wheel within the casing 40 to the shaft of which the shaft 38 is attached, as is also a shaft 41, connected, as is usual, with the rear end of the shaft of the screw 21. Preferably the motor is located on the tender, as shown, though where there is available space on the locomotive it may be mounted thereon, if desired.

In order that the elevator conduit 26 may be protected from the intense heat of the furnace, as well as to secure other advantages, the conduit is enclosed within a U-shaped water jacket 42, which is connected with the chamber of the backhead 11 at its lower and upper ends, as indicated at 43, 44, and 45, 46, respectively. This water jacket may take any preferred form, but is shown as consisting of a lower header 49 and an upper header 47, and a plurality of tubes, as 48, connecting the two headers. The water within the tubes 48 will be rapidly heated and the circulation through the water jacket will be rapid. Not only will the elevator conduit be effectually protected by the absorption of the heat by the water, but the steaming capacity of the boiler will be materially increased.

The stoking device, as described, is of high efficiency. The fuel is delivered into the fire-box from the tender with the expenditure of little power, except when there is present a considerable percentage of large lumps which must be reduced; it is elevated to a point sufficiently above the level of the fire bed to insure even distribution over the entire grate area, and to prevent, in great measure, the formation of clinkers which are apt to result from an effort to scatter the fuel by steam jets from a point but slightly above the bed of burning fuel. The hand-firing opening is not obstructed, making it easy to trim the fire by hand when necessary, and

leaving an unobstructed view for inspection.

Furthermore, the stoking mechanism occupies so little space within the fire-box that the area of the grate for combustion is not appreciably encroached upon. The parts within the fire-box are easily assembled for repairs or replacement, and are so well protected from the heat as to require but little attention of this kind.

The water jacket is not only of such a character that it occupies but little space, but it is of high efficiency both as a protection to the stoker parts, and as an adjunct to the boiler.

While the stoker as described is of a highly desirable form, nevertheless, various structural changes are possible within the scope of the invention.

We claim as our invention:

1. In combination, a locomotive having a fire-box and a hollow backhead, the backhead having a fuel admission aperture near its bottom, a tubular ball and socket unit, one element of which is secured to the outer face of the backhead and surrounds the aperture therein, and a fuel transfer conduit in sliding connection with the other element of the unit.

2. In combination, a locomotive having a fire-box and a hollow backhead, the backhead having a fuel admission aperture near its bottom, a tubular ball and socket unit, one element of which is secured to the outer face of the backhead and surrounds the aperture therein, a fuel transfer conduit in sliding connection with the other element of the unit, and an elevating conduit within the fire-box, receiving from the aperture and extending upwardly approximately parallel with and secured to the backhead.

3. In combination, a locomotive having a firebox and a backhead provided with a fuel opening therein, said backhead being also provided with an aperture below the level of said opening for the admission of fuel, an elevator casing within said firebox adjacent to said backhead and rigidly connected thereto, said casing being in communication with said aperture, a sectional fuel transfer conduit having its forward terminal section rigidly connected to said backhead in communication with said opening, and a helical screw in the rear portion of said conduit for transferring fuel along said rear portion and forcing the same through said forward section and said aperture into said casing.

4. A locomotive having a firebox, the backhead of which is chambered and is apertured adjacent its bottom for the admission of fuel, an elevator casing within the firebox attached to the backhead and communicating with the aperture therein, a screw elevator in the casing, means for driving the screw, and a jointed conveyor conduit having its forward terminal portion rigidly connected to said back-

head and in axial alinement with the aperture therein for conducting fuel from a source of supply to the aperture in the backhead.

5. In combination, a locomotive having a firebox and a backhead provided with a mud ring, the backhead having a fuel admission aperture therein immediately above said mud ring, a tubular ball and socket unit forming a single passage communicating with said aperture, one element of said unit being secured to the outer face of the backhead and surrounding said aperture, and a fuel transfer conduit in sliding connection with the other element of said unit.

10 15 In testimony whereof we affix our signatures.

NATHAN M. LOWER.
E. ARCHER TURNER.
